US00D765472S

(12) **United States Design Patent** (10) Patent No.: **US D765,472 S**
(45) Date of Patent: ** Sep. 6, 2016

(54) **SLEEVE FOR A LIQUID CONTAINER**

(71) Applicants: **Paul Metaxatos**, Swampscott, MA (US); **Joel Nevin**, Portsmouth, NH (US); **Steffen Koury**, Everett, MA (US); **Nicholas Varjabedian**, Middleboro, MA (US); **Brendan Crawford**, Newton, MA (US)

(72) Inventors: **Paul Metaxatos**, Swampscott, MA (US); **Joel Nevin**, Portsmouth, NH (US); **Steffen Koury**, Everett, MA (US); **Nicholas Varjabedian**, Middleboro, MA (US); **Brendan Crawford**, Newton, MA (US)

(73) Assignee: **Aquasana, Inc.**, Austin, TX (US)

(**) Term: **14 Years**

(21) Appl. No.: **29/519,764**

(22) Filed: **Mar. 6, 2015**

(51) LOC (10) Cl. **07-06**

(52) U.S. Cl.

(57) **CLAIM**

The ornamental design for a liquid container, as shown and described.

DESCRIPTION

FIG. 1 is a top perspective view of a liquid container showing our new design;

FIG. 2 is a bottom perspective view thereof;

FIG. 3 is a rear view thereof;

FIG. 4 is a front view thereof;

FIG. 5 is a left side view thereof; and,

FIG. 6 is a right side view thereof.

The broken lines in the drawing depict portions of the liquid container that form no part of the claimed design; the dash-dotted line in the drawing indicates the bounds of the claimed design and otherwise forms no part of the claimed design.

1 Claim, 6 Drawing Sheets
